Charles E. Barkstrom.
By Chas. A. Linnan
his Attorney:

UNITED STATES PATENT OFFICE.

CHARLES E. BARKSTROM, OF CHICAGO, ILLINOIS.

ORGAN PIPE.

Application filed July 15, 1921. Serial No. 484,861.

To all whom it may concern:

Be it known that I, CHARLES E. BARKSTROM, a citizen of the United States, residing at Chicago, county of Cook, and State 5 of Illinois, have invented certain new and useful Improvements in Organ Pipes, of which the following is a specification.

This invention has general relation to improvements in pipe organs, and particular 10 relation to the pipes thereof, and it consists in certain peculiarities of the construction, novel arrangement and combination of the various parts thereof as will be hereinafter more fully set forth and specifically claimed.

15 The principal object of the invention is to provide an organ pipe of such construction and arrangement of its parts, that the pipe as a whole may be readily and properly mounted on and in communication with the 20 wind-chest of an organ, and in such a manner that when so mounted its parts can be easily adjusted for changing or regulating tones or for cleaning or repairing parts of the device.

25 In the accompanying drawing which serves to illustrate an embodiment of the invention—

Fig. 1 is a central vertical sectional view of the pipe taken on line 1—1 of Fig. 2 looking in the direction indicated by the arrows.

30 Fig. 2 is a front view in elevation showing the pipe shortened for convenience of illustration.

Fig. 3 is an enlarged cross-sectional plan view taken on line 3—3 of Fig. 1 looking in the direction indicated by the arrows.

35 Fig. 4 is a similar view taken on line 4—4 of Fig. 1 as indicated by the arrows.

Fig. 5 is a detached perspective view of 40 a modified form of the coupling sleeve employed for uniting the lower end of the pipe to the foot thereof,

Fig. 6 is a detached perspective view of the locking device for said coupling, and

45 Fig. 7 is a side view of the key to be used for adjusting the movable cap of the device.

Corresponding numerals of reference refer to similar parts throughout the different views of the drawing.

50 The reference numeral 10 designates a portion of the wind-chest of an organ within a suitable opening 11 in the upper portion of which is located the lower end of the foot 12 of the pipe. This foot may be made of

55 any suitable material but by preference of wood. As shown, the foot 12 is downwardly

tapered at its lower portion, but is annularly enlarged as at 13 above its longitudinal middle. At the upper end of the enlarged portion 13 the foot 12 is provided with a reduced and upwardly extended portion 14, which portion has at its upper end an inwardly extended flange or closure 15 for the upper portion of the chamber or cavity 16 in the foot 12, which cavity, it will be observed, is of greater diameter than the bore or channel 17 with which the foot is longitudinally provided. By providing the foot with the reduced portion or extension 14, it is obvious that an external shoulder 18 will be provided, against which the lower end 60 of the pipe 19 will rest when said pipe is fitted on the foot.

65 By reference to Figs. 1 and 4 of the drawing, it will be seen and understood that the inwardly extended flange or closure at the upper end of the reduced portion 14 is segmental in shape and is provided with an upwardly and outwardly beveled straight edge 20 which co-operates with the 70 slidable cap 21 as well as the upper cap 22 of the pipe for producing sounds. At the straight edge of the flange or closure 15 the reduced extension 14 is cut away longitudinally, thus providing spaced walls 23, on which the 75 slidable cap 21 may rest for the purpose of partially closing the cavity or chamber 16 of the reduced portion 14 of the foot 12 of the device. The cap 21 has a plane inner surface to rest on a similar surface 21^a provided on the enlarged portion 13 of the foot 12 and extended longitudinally therewith. The outer surface of the cap 21 is 80 arcuate in form to fit snugly yet movably between the coupling sleeve and foot of the device 85 as will be presently explained.

90 The coupling sleeve is designated as a whole by the numeral 24, and may be made of any suitable size and material, but preferably of sheet metal bent to form substantially a split tube of a sufficient size to fit snugly around the lower portion of the pipe 19 and that portion of the foot 12 directly below the lower end of said pipe. This 95 sleeve has at its upper end laterally extended and spaced ears or flanges 25, which, when the sleeve is in its operative position on the device, will straddle the elongated opening in the lower end of the pipe 19 which coincides with the cut away portion of the reduced part 14 of the foot. The adjacent 100 edges of the sleeve 24 below the ears 25

thereof are each provided with interlocking tongues 26 which are bent outwardly and then inwardly to form hooks or engaging guides for a key 27 which is slightly tapered 5 towards its lower end and has said end rounded as is clearly shown in Fig. 2 to enable it to be easily inserted between the engaging hooks 26 of the sleeve. This key is provided at its upper end with an S-shaped extension 28 which serves the double function of forming a catch by means of which the key can be inserted and removed from between the hooks 26, and what is known in the art as a beard 29. The beard 15 29 on the key 27 is employed in connection with a "string" tone pipe, but may be omitted when used in connection with a "flue" tone pipe.

As the surface of the enlarged portion 13 20 of the foot below and in alignment with the slot or cut-away part of the reduced portion 14 thereof is flattened, and as the tubular portion of the coupling sleeve 24 surrounds the foot at said flattened portion, it is evident that the slideable cap 21 can be inserted 25 between said sleeve and foot by placing the upper end of said cap between said parts and forcing it upwardly until its upper end approaches the straight edge of the flange or closure 15 as will be readily understood by reference to Figs. 1 and 2 of the drawing. When thus positioned, the key 27 can be inserted between the catches 26 which operation will cause the adjacent edges of the 30 sleeve to be drawn towards each other and thus tightly hold the coupling sleeve in position on the lower end of the pipe 19 and the upper portion of the foot 12 of the device.

To un-couple or disconnect the parts, it is 40 manifest that the key 27 may be removed by upward pressure thereon, thus freeing the same from the hooks 26 and thereby allowing the sleeve to expand to a sufficient extent to permit it being slid up or down, or 45 if desired, the above operation can be employed when it is necessary or desirable to adjust the beard on said key with respect to the lips of the pipe.

In Fig. 5 I have shown a modification in 50 the construction of the coupling sleeve, which consists of a piece of sheet metal bent to form a split tubular member 30 which is provided as in the other construction with spaced parallel ears 25 in its upper portion 55 to straddle the elongated slots or openings in the lower end of the pipe and in the upper end of the reduced portion 14 of the foot. In this modification, that portion of the sleeve 30 below the ears 25 thereon has its 60 adjacent edges each provided with an outwardly turned hook 31 which hooks converge upwardly as is clearly shown in Fig. 5 of the drawing.

To clamp and lock the sleeve of the modified form in place on the pipe 19 and foot 12,

I employ a key 32 of sheet metal which is provided at each of its edges with an inwardly turned flange 33 to engage the outwardly turned hooks 31 of the sleeve 30. The flanges 33 of the key 32 converge upwardly to the 70 end that, by placing the lower part of the key 32 over the upper ends of the hooks 31, and then sliding the key downwardly thereon, said hooks will be forced towards each other and thus tightly clamp the sleeve on 75 the pipe and body.

As is clearly shown in Fig. 1, the lower end of the foot 12 has fitted therein a tubular toe 34, which toe is made of soft metal and is provided in its tapered lower end with an orifice 35 which can be enlarged if desired, by the insertion of a suitable instrument 80 therein for gouging out or cutting away said opening to the end that a greater volume of air may be permitted to pass into the 85 pipe from the wind-chest.

The toe 34 is located in a vertical opening 36 in a partition of the wind-chest directly below the opening 11 in which the foot is located. The lower end of the toe 34 is positioned about flush with the lower surface of said partition and is closed by means of a valve 37 connected to a pneumatic 38 which may be operated by a key (not shown) of the organ united to said pneumatic by means 90 of suitable connections 39 leading through the floor of the wind-chest.

In order to readily adjust the slideable cap 21, I provide the foot 12 on its front face at a suitable distance below the coupling 100 sleeve with an opening 40 for the reception of the heel 41 on the blade 42 of the key shown in Fig. 7 of the drawing. The blade 42 of this key is adapted to fit in an open slot 43 near the lower end of the cap 21, 105 when, it is manifest that by turning the blade 42 in the proper direction, the said cap may be suitably adjusted.

Having thus fully described my invention, what I claim as new and desire to secure by 110 Letters Patent is:

1. A flue organ pipe comprising a pipe having at one of its ends an opening, a hollow foot extended into said end of the pipe and having in its wall an opening coinciding with the pipe opening and provided at said end with an inwardly extended flange, a coupling uniting the pipe and foot, a slideable cap co-operating with the coupling, foot, and pipe to partially close the 115 openings in said foot and pipe, and an orifice 120 tubular toe located in the end of the foot opposite its flange and adapted for communication with a supply of air under pressure.

2. A flue organ pipe comprising a pipe having at one of its ends an elongated opening, a hollow foot extended into said end of the pipe and having in its wall an elongated opening coinciding with the pipe 130

opening and provided at said end with an inwardly extended flange having at the opening in the foot an outwardly beveled straight edge, a coupling uniting the pipe and foot, a slidable cap co-operating with the coupling, foot, and pipe, to partially close the openings in said foot and pipe, and an orificed tubular toe located in the end of the foot opposite its flange and adapted for communication with a supply of air under pressure.

3. A flue organ pipe comprising a pipe having at one of its ends an opening in its wall, a hollow foot extended into said end of the pipe and having in its wall an opening coinciding with the pipe opening and

provided at said end with an inwardly extended flange, a sleeve coupling uniting the pipe and foot, said coupling consisting of a split tubular member adapted to surround the lower end of the pipe and the upper portion of said foot and having spaced and outwardly extended flanges striding the openings in the pipe and foot and provided at its adjacent edges below said flanges with hooks, means for engagement with said hooks for forcing the edges of the coupling towards each other, and an orificed tubular toe located in the end of the foot opposite its flange and adapted for communication with a supply of air under pressure.

CHARLES E. BARKSTROM.
